BOAT PROPULSION DEVICE

Anthony A. Woods, Ridgefield, Wash.

Application November 3, 1947, Serial No. 783,769

5. Claims. (Cl. 115—16)

1

This invention relates to improvements in propulsion for small boats.

Objects of the invention are to provide a novel boat propulsion system in which the propeller is protected from weeds, sticks and rocks in the water, and from grounding on shallow bottoms, to provide a novel inboard mounting for a so-called outward motor, and, more particularly, to provide a novel well for mounting an outboard motor in the boat to draw in water through bow tubes and discharge the water through a stern tube to propel the boat. Still further objects of the invention are to provide a novel water-tight well within the boat extending above the water level for mounting an outward type motor with its propelling screw in communication with bow and stern tubes, to provide a novel mounting arrangement for the outboard motor in said well, and to provide a novel arrangement for confining the stream of water delivered by the propeller to discharge a jet of water out the stern tube and prevent churning within the well.

In the application of the present invention, a pair of bow tubes are arranged to draw in water from the bow end of the boat, so that the water thus drawn in may be acted upon by a propeller and discharged forcibly through a stern tube to drive the boat. The bow tubes communicate with the stern tube in a water-tight well having sides extending above the water level and arranged to support a cover upon which is mounted the outboard motor used for driving the boat. The stream of water from the propeller is confined and directed through the stern tube by a short tube section connected between the bow and stern tubes within the well. This intermediate tube section is arranged to enclose the propeller and support the weight of the motor, and is made readily detachable, both from the motor and from the bow and stern tubes so that the motor may easily be removed from the boat when desired. In this way the propeller is protected from floating and submerged objects in the water so that the boat may be driven safely through weeds or over submerged rocks or sand bars, or dragged up on a dock or beach, without danger of damaging the propeller.

Other objects and advantages reside in the details of construction and arrangement of parts described in the following specification and shown on the accompanying drawings illustrating a preferred embodiment of the invention. Various changes in the construction will occur to persons skilled in the art, and all such modifications within the scope of the appended claims are included in the invention.

2

In the drawings:

Figure 1 is a plan view of a boat embodying the present system of propulsion;

Figure 2 is a side elevation view of the boat;

Figure 3 is a stern view;

Figure 4 is a cross sectional view of the boat taken near the bow;

Figure 5 is an enlarged view in side elevation showing the construction of the well and the mounting of the motor therein;

Figure 6 is a cross sectional view taken on the line 6—6 of Figure 5; and

Figure 7 is a top plan view of the cover for the well.

15 In the present construction as shown in Figures 1 and 2, the boat 10 is provided with a pair of inlet tubes 11 communicating with bow openings 12 on the opposite sides of the boat below the water line. The inlet tubes 11 converge into a well 13 where they connect with a discharge tube 14 leading to a stern opening 15 below the water line 16. A motor 20 having a screw propeller 21 is mounted on the well 13 to draw water in through the inlet openings 11 and discharge it 20 forcibly through the discharge tube 14 to drive the boat forward. Suitable screens may be provided in the tubes 11 or openings 12 to keep out solid material. The boat is steered by a pair of 25 rudders 22 mounted on opposite sides of the stern opening 15.

30 The principal features of novelty in the present arrangement reside in the construction of the well and tubes and the mounting of the motor, as shown in Figures 5 and 6. The inlet tubes 11 35 may converge to a point of intersection before they reach the well 13, they may intersect where they pass through the wall of the well, or they may enter the well individually and be joined together therewithin, but in any case the tube 40 or tubes are welded to the well as indicated at 24, or provided in some other satisfactory manner with a water-tight joint to prevent leakage of water into the boat. It is appreciated that different forms of joints may be employed and that different materials may be used for making 45 the well and tubes, but in the present embodiment the tubes 11 and 14 and the well 13 are made of sheet metal and the tube 14 is similarly connected with the after side of the well by a weld or some other form of water-tight joint. The well 13 in the present embodiment is cylindrical in shape, having walls extending up above the water level 16 and provided with a bottom 25 50 which may rest on or be attached to the bottom of the boat.

55 The top rim of the well is provided with a rolled

edge or bead 26 to support a reinforced, arched cover 27 having a lip 28 resting on the bead 26 and a flange 29 extending therewithin to make a close fit in order to provide a fairly rigid mounting for the motor 20 which passes through the center of the cover 27 and is held thereby in a stationary upright position. The motor 20 may take various forms and may be specially designed for the present purpose, but in the illustrated embodiment a conventional motor of the so-called outboard type is shown, this type of motor having the usual mounting bracket 30 for mounting on the stern of a rowboat or the like with the vertical drive housing 31 extending down into the water. In the present use of the motor the conventional mounting bracket 30 is not used, and may be removed if it is in the way of the cover 27. The cover 27 is provided with a plurality of brackets which may comprise vertical sheet metal fins 32 having bottom flanges 33 secured to the cover to hold the motor in a vertical position with the housing 31 extending through a central opening 34 in the cover, as shown in Figures 5 and 7. To permit installation and removal of the motor, the cover 27 is made in two halves with a standing seam 35 intersecting this opening. The seam 35 may comprise vertical flanges on the two cover sections adapted to be bolted together to encircle the motor housing 31. Other mounting adaptations for the motor may be devised on the cover. A plurality of clamps 41 are provided to secure the cover 27 to the sides of well 13.

The tube 14 is preferably circular and is cut off on a bevel and provided with an end flange 42 within the well 13, and the common opening of the intersecting tubes 11 is preferably of the same shape and size and provided with a similar end flange 43 within the well. A short removable tube section 45 is provided to surround the propeller 21 and interconnect the tubes 11 and 14 to provide a smooth channel for streamlined flow of the water approaching and leaving the propeller. The section 45 has an end flange 46 to be connected with the flange 42, and an end flange 47 for connection with the flange 43, to hold the section in place between the inlet and outlet tubes. The section 45 is preferably made of flexible sheet metal, open on its top side in a longitudinal joint so that it may be sprung apart to receive the propeller 21 and the lower end of the vertical housing 31. Top flanges 48 provide for closing the top of the tubular section 45 after it has been placed around the propeller, each flange 48 having a semicircular portion or half collar 49 to surround and engage the housing 31. The various flanges may be secured together by bolts 50 or other suitable means. If desired, gaskets may be provided in all of these flange joints to make water-tight connections, and a suitable gasket may be provided for the collar 49, but this is not necessary because these parts are all confined within the water-tight well 13. There is no objection to permitting the water to rise in the well 13 to its natural water level, because the primary purpose of the intermediate section 45 is merely to confine the flowing water to a streamlined channel for efficient operation. The installation and removal of the motor is facilitated if no attempt is made to make the flange connections water-tight.

Outboard motors of the type shown usually have a vertical fin or guard 55 extending beneath the propeller 21, and in the present construction it is preferred to utilize this fin to support the weight of the motor rather than to have

this weight hang on the cover 27, although the motor may be supported in the latter manner, if desired. Thus, for the purpose of supporting the motor, there is preferably provided a cup or socket 56 in the bottom of the tube section 45 to engage the end of the fin 55 in the manner shown. A saddle 57 is disposed under the tube section 45, as shown in Figure 6, to support the weight on the socket 56. The weight of the motor is thereby brought to bear on the bottom 25 of the well, where it is distributed over the bottom of the boat, so that the principal function of the cover 27 and brackets 32 is merely to brace the motor and hold it in an upright position. It is, of course, appreciated that the motor is not required to turn in the well, but is mounted in a fixed position, inasmuch as steering of the boat is accomplished by the rudders 22.

With this mounting arrangement, the outboard motor may be considered and used as a permanent installation in the boat, and in such case further refinements may be made in the mounting of the motor, but the construction is also intended to be used with conventional outboard motors which have not been modified or rebuilt for the present purpose and which are intended to be removed after each use of the boat. Other changes will suggest themselves, depending upon the manner of use in a particular case, and it is, therefore, intended that the invention not be limited to the precise construction illustrated in the drawings.

The manner of installing and removing the outboard type motor 20 will be best understood by first describing the removal procedure with reference to Figure 5 which shows the motor installed. The cover clamps 41 are first unfastened and the bolts removed from cover flanges 35. The motor is then lifted an inch or so to permit raising the two sections of cover 27 to disengage flanges 29 from bead 26 for removal of the cover sections. The collar parts 49 ordinarily do not engage the housing 31 so tightly as to prevent lifting of the motor, but if these collar parts are gasketed and do clamp too tightly against the housing 31 to permit any sliding movement, then the flanges 29 on the cover sections should be disposed on the outside of bead 26 to permit removal of the cover sections without lifting the motor. After removal of the two sections of cover 27, the motor may be again rested on its bottom fin 55 and steadied by an assistant while the bolts are removed from flanges 48 and the upper portions of the mating flanges 42, 46 and 43, 47. The upper parts of tube section 45 may then be sprung apart to separate the flanges 48 sufficiently to pass the propeller 21 when the motor is lifted vertically upward. If the motor is not to be used in another boat, the bolts may be left in flanges 48 and all the bolts removed from end flanges 42, 46, 43 and 47. Then the tube section 45 may be removed bodily with the motor.

In installing the motor the foregoing operations are reversed, the cup or socket member 56 serving to center the lower end of fin 55 in its proper position when the fin is brought to bear thereon. After the bolts have been replaced in the flanges of tube section 45, the motor is raised an inch or so by sliding housing 31 through the collar parts 49 to permit replacement of the two sections of cover 27. Then the flanges 35 are fastened together and clamps 41 secured so that the motor can be lowered into its operating position with fin 55 again resting in cup 56.

When the motor is thus lowered, the cup 56 automatically guides the fin 55 to centered position without requiring visual observation of these parts for proper manipulation. When the collar parts 49 are equipped with gaskets to engage the vertical housing 31 snugly, the use of outside flanges at 29 instead of inside flanges permits the two sections of cover 27 to be replaced without lifting the motor.

Having now described my invention and in what manner the same may be used, what I claim as new and desire to protect by Letters Patent is:

1. In a boat, a well having a bottom within the boat and a side wall around the well extending above the level of the water line of said boat, horizontal water inlet and discharge tubes sealed in said well, a removable horizontal cylindrical tube section in said well interconnecting said inlet and discharge tubes, a cover on said well, outboard motor supporting means in said tube section, and additional outboard motor supporting means on said cover, said tube section having a top opening to receive a vertical drive shaft of an outboard motor supported on said means.

2. In a boat, a well having a bottom within the boat and a side wall extending above the level of the water line of said boat, horizontal water inlet and discharge tubes sealed in said well, a removable horizontal flexible tube section for propulsion means in said well interconnecting said inlet and discharge tubes, a propulsion motor support in the bottom of said tube section, a longitudinal joint extending along the top of said tube section, and removable securing means for said joint whereby said tube section may be opened at said joint for access to the interior of the tube section in installing and removing said propulsion means.

3. In a boat, a well having a bottom within the boat and a side wall extending above the level of the water line of said boat, horizontal water inlet and discharge tubes sealed in said well, a horizontal cylindrical tube section for propulsion means in said well interconnecting said inlet and discharge tubes, a propulsion motor support in the bottom of said tube section, and detachable connecting means securing the ends of said tube section to said inlet and discharge tubes, said

tube section being removable from the top of said well.

4. In a boat, a well having a bottom within the boat and a side wall extending above the level of the water line of said boat, horizontal water inlet and discharge tubes sealed in said well, a horizontal cylindrical tube section in said well interconnecting said inlet and discharge tubes, detachable connecting means for securing the ends of said tube section to said inlet and discharge tubes, a longitudinal joint in the top of said tube section, detachable connecting means for said joint, and an opening in the top of said tube section intersecting said joint for propulsion means, said tube section being flexible for installing and removing said propulsion means by removing certain of said connecting means and spreading said longitudinal joint.
5. In a boat, a well having a bottom within the boat and a side wall extending above the level of the water line of said boat, horizontal water inlet and discharge tubes sealed in said well, a horizontal tube section in said well interconnecting said inlet and discharge tubes, a motor support in the bottom of said tube section, a cover on said well having a separable joint extending across the well, detachable means for securing the two parts of said cover together at said joint, and additional motor supporting means on said cover.

ANTHONY A. WOODS.
